UNITED STATES PATENT OFFICE

HENRY S. DILLS, OF GARRETT, INDIANA, ASSIGNOR OF ONE-HALF TO JAMES HEDSONS, INCORPORATED, OF DOWAGIAC, MICHIGAN, A CORPORATION OF MICHIGAN

DESIGN FOR A SURFACE ORNAMENTATION FOR ARTIFICIAL BAIT.

58,139.

Specification for Design.

Patented June 14, 19

Application filed June 17, 1918. Serial No. 240,514. Term of patent 14 years.

To all whom it may concern:

Be it known that I, HENRY S. DILLS, a citizen of the United States, residing at Garrett, in the county of Dekalb and State of Indiana, have invented a new and useful Design for Surface Ornamentation for Artificial Bait, of which the following is a specification, reference being had to the accompanying drawings, forming a part thereof.

The figure shown in the drawings is a perspective view showing an artificial bait provided with my surface ornamentation.

I claim:

The ornamental design for a surface ornamentation for artificial bait, substantially shown.

HENRY S. DILL
